UNITED STATES PATENT OFFICE.

ASHBY J. HOCKMAN, OF LAS ANIMAS, COLORADO, ASSIGNOR OF FIFTY ONE-HUNDREDTHS TO ALFRED C. HARTMAN, OF LAS ANIMAS, COLORADO.

AUTOMATIC GAGE-GLASS VALVE.

1,302,045.

Specification of Letters Patent. Patented Apr. 29, 1919.

Application filed January 16, 1918. Serial No. 212,069.

To all whom it may concern:

Be it known that I, ASHBY J. HOCKMAN, a citizen of the United States, residing at Las Animas, in the county of Bent, State of Colorado, have invented certain new and useful Improvements in Automatic Gage-Glass Valves; and I do hereby declare the following to be a full, clear, and exact description of the invention, such as will enable others skilled in the art to which it appertains to make and use the same.

This invention is an improvement in gages for boilers and the like and has particular reference to an automatic check valve therefor.

Heretofore, in valves of known construction, wherein it is desired to check the pressure upon the breaking of a gage glass, the same have been subject to defects which render their use both undesirable and detrimental to the safety of the boiler. This has been mainly found due to the fact that springs, release pins and other constructions have been employed to open valves and these constructions have oftentimes prevented an absolutely correct registration of pressure in the gage.

An object of the invention is to overcome the above objections by providing a valve wherein the checking of the flow of pressure will be positively accomplished upon breaking of the gage glass and wherein said glass may be effectively scavenged to remove the sediment which collects therein and prevents accurate reading thereof.

Another object is to provide a valve construction of this character which is simple in construction, easy to manufacture and effective in carrying out the purpose for which it is designed.

The inventive idea involved is capable of receiving a variety of mechanical expressions one of which, for the purpose of illustrating the invention, is shown in the accompanying drawing, wherein:

Figure 1 is a fragmentary side elevation of a boiler and gage glass therefor showing the invention applied.

Fig. 2 is a vertical longitudinal section.

Fig. 3 is a detail side elevation of a valve seat employed in connection with the invention.

Fig. 4 is a transverse sectional view thereof.

55 In the drawing, the numeral 5 indicates a

portion of a boiler or other fluid pressure source with which is associated the gage glass 6 which may be of any desired construction and which has its upper end connected to the boiler in any preferred manner.

The automatic valve construction which embodies the essential feature of this invention is associated with the lower end of the gage glass and preferably comprises a valve body or casing 7 having an extension 8 adapted to be connected to the boiler 5 and provided with a passage 9 which communicates, at its end remote from the boiler, with the right angularly disposed passage 10 in longitudinal alinement with an extension 11 to which is adapted to be connected a globe valve, gate valve or cock valve (not shown) which provides for draining the gage glass whenever desired.

The valve body 7 is preferably enlarged as indicated at 12 and provided in said enlargement with the screw threads 13 which are engaged by an externally threaded ring member 14 which, when in position, is recessed within said enlargement and which is provided centrally thereof with an opening 15 in alinement with the gage glass 6 and having a valve seat 16 at its inner or lower end. The outer surface of the ring member 14 may be provided with recesses or sockets 17 to receive a suitable tool whereby the member may be removed or replaced. The lower end of the gage glass 6 rests upon the outer or upper surface of the ring member 14 and is surrounded by the packing 18 which also engages the outer face of said ring member and said packing is held in position by means of the packing gland 19 secured in place by the gland nut 20 which is internally threaded to engage the external threads 21 of the enlargement 12.

Directly below the point of communication of the passage 9 with the passage 10, the wall of the latter is screw threaded as indicated at 22 to receive the external threads of the valve seat 23. The upper portion of the seat 23 is preferably formed by a plurality of upwardly converging and spaced webs 24 forming ports 25 therebetween and said webs and ports give to the upper portion of said seat a general frustoconical appearance. The upper ends of the ports 25 terminate short of the adjacent ends of the webs 24 and the upper end of the seat

is preferably concaved as indicated at 26 and provided with an opening 27 which communicates with the ports 25 and the longitudinal passage 28 formed in the lower end of the seat 23. A ball valve 29 is preferably employed in connection with the invention and is normally seated in the concaved upper end of the member 23 so as to permit of the free passage of pressure through the gage glass and extension 9. In order to cut off the pressure on the automatic valve, the extension 9 is provided therein with a valve seat 30 adapted to be engaged by a valve 31 which may be of any desired construction and which has a stem 32 mounted in the bushing 33 so as to be adjustable into engagement with said seat 30.

In practice, as previously stated, the ball valve 29 is in engagement with the upper end of the seat 23 but should the gage glass break, as often occurs, the pressure escaping through the break will immediately lift the valve 29 and cause the same to engage the seat 16 in the ring member 14 thus stopping the flow of pressure through the passage 15 and the lower portion of the gage glass remaining in the valve body. This valve 29 will remain seated until the pressure is cut off and it will thus be apparent that danger from escaping steam or other fluid will be prevented. Should it be desired to scavenge the gage glass, the drain valve (not shown) which is attached to the extension 11 may be

opened and the pressure will then be directed through the valve body in such a manner as to retain the valve 29 seated in the upper end of the member 23 and thus permit of the sediment and dirt in the gage glass being forced therefrom and through the ports 25 and outwardly through the extension 11.

What is claimed is:—

An automatic valve structure for gage glasses comprising a valve body adapted to be connected to one end of a gage glass and having an extension in alignment with the gage glass and a second extension at an angle thereto and adapted to be connected to a source of pressure, a ring member mounted in said valve body below said second extension and having a longitudinal passage in alignment with the first mentioned extension and also provided with spaced webs forming ports therein and a valve seat, a member fitted in the first named extension and having a valve seat and a ball valve normally engaged with the first named valve seat and adapted to engage the seat in said second named member to cut off the pressure through said gage glass.

In testimony whereof, I affix my signature, in the presence of two witnesses.

ASHBY J. HOCKMAN.
